UNITED STATES PATENT OFFICE.

PATRICK DOHERTY, OF PHILADELPHIA, PENNSYLVANIA.

SELF-REGISTERING FAUCET.

No. 814,945.

Specification of Letters Patent.

Patented March 13, 1906.

Application filed July 3, 1905. Serial No. 268,063.

To all whom it may concern:

Be it known that I, PATRICK DOHERTY, a citizen of the United States, residing at Philadelphia, in the county of Philadelphia and 5 State of Pennsylvania, have invented a new and useful Self-Registering Faucet, of which the following is a specification.

This invention relates to self-registering faucets in which each delivery is automatically indicated. Its objects are, first, to provide a faucet of this character which shall reliably fulfil its requirements; second, to provide a faucet adapted to deliver liquids only when a suitable receptacle is properly positioned to receive the effluent; third, to so arrange and construct the same that the parts are simple, economically manufactured, and not easily disarranged when assembled. These and other minor objects are attained 15 by the novel combination of parts hereinafter fully described, and shown in the accompanying drawings, in which—

Figure 1 is a plan view of my invention. Fig. 2 is a vertical section taken on line *a a* of 25 Fig. 1. Fig. 3 is a partial front elevation showing the register.

Similar characters refer to similar parts throughout the several views.

The flange 1 is secured, as usual, against a 30 suitable support, as the side of a tank or fountain, and is connected with the source of liquid-supply direct or by piping. From the flange is the connecting member 2, of such length that the handles may be readily operated. The body 4 is bored transversely for 35 the plug 15, which is adapted to control the flow of liquid by operation of the handle 3. To the extension 6 of the body 4 is attached the delivery-spout 7. Thus far the faucet 40 corresponds in most respects to those of ordinary construction, the liquid entering at the flange end and passing out at the spout, the said passage being under the ready control of operator.

Within the spout 7 is loosely contained the 45 pin 8, having at its lower end a small knob 9, extending below the bottom of the spout. Midway in length of the spout is a concave annular seat 7^a, in which is adapted to normally rest the conical valve 10, attached to 50 the pin 8. Above the valve is the rod 11, passing through the stuffing-box 6^a and having immediately above the nut 6^b a rigidly-affixed collar 12, adapted to contact with the 55 outer end of the locking-lever 13.

The spring 14 is kept in position by the ex-

tension of the rod 11 and in compression between the casing and end of lever 13, its functions being to depress the pin 8, keep the valve 10 against its seat, and through the lever to maintain the faucet-plug 5 in a closed position.

The lever 13 has a pivoted fulcrum at 15 and its opposite end formed into a catch 16, adapted to engage with the notch 17 in the ratchet-disk 18, integral with the stem of the plug 5. Also on this ratchet-disk is the projection 19, adapted to contact with and raise the plunger-rod 20 of the register 21 when the plug-handle 3 is moved to open the faucet. The 70 said register 21 is not part of this invention, but shows merely as representative of any which it may be preferred to use. It is securely attached to the upper part of the faucet in such manner as not to interfere with the functions thereof, but be visible to the operator. The remainder of the mechanism, with the exception of the operating-plug handle, spout, and pin-knob, is preferably 75 enclosed by a suitable casing 22.

In operation the receptacle in which it is desired to draw liquid from the faucet, as an ordinary drinking-glass, is placed below the spout in such manner that the bottom is brought into contact with the knob 9, causing it to raise, thereby releasing the ratchet and freeing the handle ready to be turned to open the passage in the faucet. The movement of the handle is indicated on the dial, which is assumed to move forward and add 90 one to the index. When the receiving-glass is removed, the pin 8 returns to place, the enlargement 10 seating at 7^a and cutting off most of the flow should the operator neglect to close the faucet. When the handle is 95 turned, so that no liquid is passing, it must remain in such closed position until the pin be again raised.

Having thus described my invention, what I claim, and desire to secure by Letters Patent, is—

1. In a self-registering faucet, the combination with a faucet-body, a handled plug therefor and a register of ratchet-teeth on the said plug, a pawl adapted to engage the ratchet, means for operating the pawl, and means for actuating the said register, all substantially as shown and described.

2. In a self-registering faucet, the combination with a body, a plug therefor and a suitable register, of means for securing the plug while closed, means for releasing the plug

and means for actuating the said register, all substantially as shown and described.

3. In a self-registering faucet, the combination with a faucet-body, an operative plug therein and a suitable registering means, of a globular valve-seat within the spout of the said faucet-body, a valve, extending below the spout-opening, a rod attached to the valve and passing outward through the upper part of the said faucet, a catch on the said plug, a detent combined therewith adapted to be operated by the rod and a projecting member integral with the said plug adapted to operate the said registering means, all substantially as shown and described.

4. In a self-registering faucet, the combi-

nation with a suitable faucet-body, having a handled plug and depending spout, of a valve-seat thereon, a spring-controlled valve fitted to the seat, means for operating the valve, a 20 detent on said plug, a pawl-lever combined therewith and operable by the valve, a registering device and means for operating the same combined with the said plug, all substantially as shown and described. 25

In testimony whereof I have signed my name to this specification in the presence of two subscribing witnesses.

PATRICK DOHERTY.
